UNITED STATES PATENT OFFICE.

CHARLES JACOB JOSEF STRAESSLE, OF LYNN, MASSACHUSETTS.

SHOE-HEEL-BURNISHING WHEEL.

1,120,559.

Specification of Letters Patent.

Patented Dec. 8, 1914.

Application filed September 11, 1913. Serial No. 789,231.

To all whom it may concern:

Be it known that I, CHARLES JACOB JOSEF STRAESSLE, a citizen of Switzerland, and a resident of Lynn, in the county of Essex and 5 State of Massachusetts, have invented a new and Improved Shoe - Heel - Burnishing Wheel, of which the following is a full, clear, and exact description.

The invention relates to a novel burnishing wheel especially adapted to the burnishing of shoe heels, and it is a design of the invention to provide a burnisher in which an annular burnishing means on the exterior of the wheel is adapted to yield and to automatically conform to the curvature of the heel at the point of contact.

In carrying out the invention use is made of individual rings to constitute the burnishing means, and spring elements at the inner 10 periphery of the rings, and yieldingly supporting the same, there being a clearance space at the inner periphery of the rings permitting the rings to yield individually and assume various degrees of eccentricity 15 with respect to the axis of the wheel in conforming in profile at the point of contact with the heel, to the curvature of the latter.

The distinguishing features of my invention, and the important structural elements 20 characterizing the practical embodiment which is illustrated as an example, will be more particularly explained in the specific description hereinafter to be given.

Reference is to be had to the accompanying drawings forming a part of this specification, in which similar characters of reference indicate corresponding parts in all the views.

Figure 1 is a longitudinal, sectional view 40 of a burnisher embodying my invention; Fig. 2 is a front view, with parts in section, on approximately the line 2-2 of Fig. 1; Fig. 3 is a side elevation; Fig. 4 is a separate view of a portion of one of the burnishing rings; and Figs. 5 and 6 are side elevations showing modifications of the peripheral grooves.

In constructing a burnisher in accordance 45 with my invention, a hub 10 is provided, of any approved shape and dimensions, having suitable supports 11 which may be in the form of separate forwardly extending arms on which are seated plate springs 12, these springs being secured by screws 13 or their equivalent. Around the hub a burnishing means is provided, which I form of indi-

vidual rings 14, the springs being formed with lateral spring tongues 12^a, to better permit the individual rings 14 to yield relatively to each other and assume various degrees of eccentricity with respect to the axis of the wheel.

The outer periphery of the wheel formed by the burnishing rings 14, may initially have any suitable degree of curvature, as 65 illustrated in Fig. 1 or may be non-curving as in Fig. 3. Whatever the external form of the burnisher, the rings 14 may yield radially inward to conform at the point of contact with the shoe heel A, to the curvature of the said heel. The rings in the illustrated example are held between an annular flange 10^a on the hub and a ring 15 secured to the outer end of the spring supports 11, by a screw 16 or equivalent means.

The relative arrangement of the springs 12 and burnishing means 14 is such that the rings will be engaged by the springs and prevented from creeping. I have shown the rings 14 (see Fig. 2) as formed with lugs 80 14^a projecting radially inward at the periphery of the rings, and disposed between opposite ends of adjacent tongues 12^a of the springs, so that in the turning of the wheel the springs will engage the lugs on the rings 85 and turn the latter regardless of the direction in which the wheel is turned.

In the form shown in Fig. 4, the lugs 14^b corresponding to the lugs 14^a of Fig. 2, are produced by forming notches 14^c in the 90 inner periphery of the rings 14, while in Fig. 2, the lugs 14^a project inward beyond the inner peripheral line of the ring.

The rings 14 at their outer periphery may be formed with grooves 14^d, which may 95 range parallel with the axis, as shown in full lines in Fig. 3, or these grooves may be cut diagonally, either right to left or left to right, as indicated at 14^e 14^f in Figs. 5 and 6.

The hub 10 is formed with a suitable socket or bore 10^b to receive the revolving spindle or equivalent element 17, to which the hub may be fastened by a set screw 18, or any other suitable means.

In practice, the burnishing wheel will be immersed at the bottom in a well of molten wax and a side of the wheel is placed in contact with the heel, so that in the act of burnishing, a deposit of wax will be applied to 110 the heel and the latter made ready for the polishing wheel.

The described construction affords a practical means for carrying my invention into effect, and I would state in conclusion that I do not limit myself strictly to the mechanical details hereinafter illustrated, since manifestly the same can be considerably varied without departure from the spirit of the invention.

Having thus described my invention, I claim as new and desire to claim by Letters Patent:

1. A burnishing wheel having an annular peripheral burnisher, and spring means secured to the wheel within the burnisher but unconnected therewith for yieldingly supporting the same, the said burnisher having means adapted to engage said spring means to prevent relative turning movement between said burnisher and wheel.
2. A burnisher wheel having an annular peripheral burnisher formed of separate rings, and a plurality of springs within said rings but unconnected therewith and spaced apart about the axis of said wheel, each of said springs having lateral resilient tongues for supporting each of said rings, each of said rings having a lug extending inwardly

from its inner periphery between a pair of lateral tongues of adjacent springs.

3. A burnishing wheel comprising a hub having arms approximately parallel with the axis, plate springs secured to the arms and formed with lateral resilient tongues at the sides, and an annular burnisher formed of separate rings yieldingly supported on the tongues.

4. A burnishing wheel comprising a hub having arms approximately parallel with the axis, plate springs secured to the arms and formed with lateral resilient tongues at the sides, and an annular burnisher formed of separate rings yieldingly supported on the tongues, said rings each having a lug at its inner periphery disposed between a pair of tongues of adjacent plate springs.

In testimony whereof I have signed my name to this specification in the presence of two subscribing witnesses.

CHARLES JACOB JOSEF STRAESSLE.
